CHIN SUPPORT

Will J. Bethurum, Franklin, Tenn.

Application August 21, 1934, Serial No. 740,809

1 Claim. (Cl. 27—25)

The invention relates to a chin support used by morticians for holding the mouth closed in a natural position, after death, until the effects of the embalming fluid has caused the jaws to set to the extent that the device may be removed.

The primary object of the invention is the provision of a support of this character which can be quickly and easily applied and adjusted by means of slight pressure from the thumb and index finger of the user and will not slip from its adjusted position.

Another object of the invention is the provision of a support of this character, wherein the adjustable member which rests under the chin is movable upward or downward on a square supporting rod and held in position or adjustment by means of notches on the front or chin side of the square supporting rod, so that delicate adjustment may be had.

A further object of the invention is the provision of a support of this character which is simple in construction, thoroughly reliable and effective in its purpose, easy of adjustment, easy of application and removal, strong, durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claim hereunto appended.

In the accompanying drawing:

Figure 1 is a perspective view showing the invention constructed in accordance with the invention as applied.

Figure 2 is an enlarged bottom plan view.

Figure 3 is an enlarged vertical side elevation partly in section.

Figure 4 is a view looking toward the rear of the device, the same being in elevation.

In most instances, after death, the jaw drops, holding the mouth open and giving an unusual appearance to the face. In the work of caring for the body, the embalmer is called upon to restore the natural expression of the features and in order to do this it is required that the mouth not only be closed naturally but that it be held firmly in position until "rigor mortis" has set in, or the stiffening effect of the embalming fluid has taken place. To accomplish the setting of the mouth there has been devised the present invention in the nature of a chin support which comprises a shank or stem 5, which in cross section is preferably of square formation, and on one face is provided a rack or ratchet teeth 6, these extending for a major portion of the length of said stem or shank. Upon the upper end of the stem or shank 5 is a bearing 7, while slidable upon the

said stem or shank is a carrier 8 which has formed therein the hole 9 for accommodating the said shank or stem and this hole, at one side thereof, is formed with a ratchet tooth 10 for coaction with the rack or the teeth 6, so that the carrier can be latched in its adjusted position on the stem or shank, as should be clearly apparent from Figures 1 and 3 of the drawing.

The carrier supports a concaved circular-shaped chin rest 11 which has working through its center a set screw 12 formed with a knurled head 13 and a pointed tip 14, respectively, the screw being also threaded in the carrier 8, as will be obvious. Rising from the bearing 7 is a pair of prongs 15, these having the outwardly curved portions 16 and also the right-angular end portions 17 provided with ball terminals 18, the portions 17 of the ball terminals 18 being adapted to be inserted into the nostrils, and the curved portions 16 amply clear the projecting fleshy portion of the nose, the application of the device or support being clearly illustrated in Figure 1 of the drawing.

The bearing 7 and the carrier 8 are provided with finger grips 19 which permit easy and convenient adjustment of the device, both for applying and releasing the same.

In the application of the device, the chin is brought to engagement upon the chin rest 11, it being understood, of course, that first the prongs 17 are inserted in the nasal passages and thereafter the carrier 8 is adjusted on the stem or shank 5 and through the instrumentality of the rack 6 and the tooth 10 the said carrier can be latched in its set position, so that the lower jaw will be sustained closed and the mouth assume a natural appearance.

The shank or stem 5 in its square formation and fitting a correspondingly shaped clearance or opening 9 therefor in the carrier 8 will eliminate any liability of side movement of these parts with relation to each other and accuracy in adjustment is assured. The set screw 12 also assures retention of the chin upon the rest 11 of the device, so that there is no liability of the chin slipping from said rest while the device is in use.

What is claimed is:

A chin support comprising a member to be positioned in the nostrils of a person, a flat faced rod having a head carrying said member, rack teeth formed on one flat face of the rod, a chin bearing slidably fitted on the rod and having a ratchet tongue engageable with the rack teeth thereon for latching the chin bearing adjusted on the rod when the said chin bearing is subjected to weight and means on the head and chin bearing for engagement by the fingers of a person for effecting the ratcheting action of the chin bearing on the rod.
